UNITED STATES PATENT OFFICE.

CHARLES M. LEECH, OF LIMA, OHIO.

INTERNAL-COMBUSTION ENGINE.

1,099,065.

Specification of Letters Patent.

Patented June 2, 1914.

Application filed October 8, 1912. Serial No. 724,552.

To all whom it may concern:

Be it known that I, CHARLES M. LEECH, a citizen of the United States, residing at Lima, in the county of Allen and State of Ohio, have invented certain new and useful Improvements in Internal-Combustion Engines, of which the following is a specification.

My invention relates to improvements in internal combustion engines, and has particular reference to an internal combustion engine preferably of the two cycle type, embodying novel means for regulating the feeding of the gas or fuel to the cylinder or cylinders of the same.

A further object of the invention is to provide novel means to compress the explosive charge and feed the same to the cylinder.

A further object of the invention is to provide an engine of the above mentioned character, which is strong, durable, and not liable to derangements.

Other objects and advantages of the invention will be apparent during the course of the following description.

In the accompanying drawings forming a part of this specification and in which like numerals are employed to designate like parts throughout the same, Figure 1 is a central vertical sectional view through the engine, Fig. 2 is a horizontal sectional view taken on line 2—2 of Fig. 1, Fig. 3 is a vertical sectional view taken on line 3—3 of Fig. 1, Fig. 4 is a horizontal sectional view taken on line 4—4 of Fig. 1, Fig. 5 is a side view of a stationary valve casing, Fig. 6 is a side view of a rotatable valve, and, Fig. 7 is a transverse sectional view through the rotatable valve, showing the same in a position to supply the compressed charge to the explosion cylinder.

In the drawings, wherein for the purpose of illustration, I have shown a preferred embodiment of my invention, the numeral 8 designates an explosion cylinder, which is mounted upon a lower pumping cylinder 9, having a larger diameter, as shown. Surrounding the cylinder 8 are radially disposed fins 10, inclosed within a jacket 11, provided at its upper end with an air inlet opening 12. The cylinder 8 is provided with an exhaust port 13 and a plurality of inlet ports 14, which lead into a common inlet port 15, as shown. A swinging valve 16 is disposed near the plurality of inlet ports 14 and serves to control the passage of the ex-

plosive charge into the same. Surrounding the lower cylinder 9 is an outer casing 17, providing an air space 18, which surrounds the lower pumping cylinder 9 and is in free communication with the interior of the jacket 11. The outer casing 17 has a crank case section 19 formed upon the lower end thereof, as shown, which is connected with a lower crank case section 20, for forming a closed crank case.

Mounted to reciprocate within the explosive cylinder 8 is a hollow piston 22, provided at its lower end with a pumping piston 23, of larger diameter, as shown. The piston 23 operates within the pumping cylinder 9, as shown. Extending into the piston 22 is a pitman 24, pivotally connected therewith by a transverse pin 25. The numeral 26 designates a crank shaft, provided with a crank 27, as shown. A pin 28 pivotally connects the lower end of the pitman 24 with the crank 27.

The numeral 29 designates a casting or housing formed upon one side of the outer casing 17 and provided with a central longitudinal opening 30, for receiving a stationary valve casing or seat 31, provided near its ends and upon its upper side with openings 32, having free communication with a chamber 33, as shown. This chamber discharges into a port 34, which leads into the inlet port 15, as shown. The stationary casing or seat 31 is provided intermediate its ends and diametrically opposite the openings 32, with a pair of openings 35, which lead into ports 36 and 37, as shown. The port 37 leads into a port 38, which discharges through an opening 39 into a chamber 40. The chamber 40 has communication with the pumping cylinder 9 through an opening 41, as shown. The chamber 40 is entirely closed except for the openings 39 and 41.

The numeral 42 designates a port or manifold which leads into the port 36 and has communication with the carburetor to receive the explosive charge from the same.

Rotatably mounted within the casing or seat 31 is a tubular valve 43, having both ends thereof closed by heads 44, carrying trunnions 45 and 46. The rotatable tubular valve 43 is provided intermediate its ends with an exterior pocket or recess 47, having no communication with the interior of the same. When the valve is in the position shown in Fig. 1, the pocket or recess 47 es-

tabilishes communication between ports 36 and 37, whereby the gas is supplied into the pumping cylinder 9 upon the down stroke of the engine. The tubular valve 43 is provided near its ends with openings 48, which are adapted to be moved into and out of registration with the openings 32. Openings 49 lead into the port or passage 37. It is obvious that the openings 48 of the tubular valve 43 are also adapted to move into registration with the openings 49, whereby the compressed explosive charge may be fed into the rotatable tubular valve. The tubular valve 43 is held against longitudinal displacement by securing plates 50. The tubular valve is rotated by a pinion 51, which is rigidly mounted upon the trunnion 45. The pinion 51 is driven by a pinion 52, which is rigidly mounted upon the crank shaft 25.

Leading into the chamber 33 is a pipe 33^a, connected with the upper end of a pipe 42^a, which leads into the chamber 42. A pressure relief valve structure is mounted in the upper end of the pipe 42^a to normally prevent the back flow of gas, but permitting the same to return to the chamber 42 when the pressure in the port 34 exceeds a certain limit. This valve structure includes a shell 54, formed of the upper end of pipe 42^a within which is mounted a holding casing 55, receiving a valve stem 56 of a downwardly opening valve 57. This valve is normally held seated by a spring 58 of the desired stiffness. A clamping ring 59 retains the holding casing 55 in its proper position and this clamping ring is normally covered by a cap 60.

The crank case sections 19 and 20 are provided respectively with fly-wheel casing sections 61 and 62, which form a fly-wheel casting having free communication with the air-space 18 through an opening 63. The fly-wheel casting has its outer side formed entirely open, as shown. Rigidly mounted upon the crank shaft 26 is a combined fly-wheel and fan 64, provided upon its periphery with ribs or vanes 65, disposed at an angle with relation to the wheel 64, as shown.

The operation of the engine is as follows:—When the piston 22 starts upon its downward movement, the pocket 47 is brought into a position to establish communication between ports 36 and 37, whereby the pumping piston 23 sucks gas into the pumping cylinder 9. By the time the piston 23 has reached its lowermost position to uncover the exhaust port 13, the openings 48 are in registration with the openings 32, whereby the compressed charge contained within the valve 43 is fed through port 15 and ports 14 into the lower end of the cylinder 8, while the products of combustion are being expelled therefrom. The piston 22 now travels upwardly, to entrap the fresh

charge fed therein and compress the same prior to the time when the same is fired, which, of course, occurs when the piston is just about to start upon its downward movement. When the piston 23 moves upwardly it compresses the charge fed in the cylinder 9, which charge is now fed into the valve 43 when the openings 48 move into registration with the openings 49, which occurs when the piston 22 is nearing its uppermost position. In this way the compressed charge is stored within the rotatable valve 43 until the openings 48 thereof move into registration with the openings 32, as above explained. The fly-wheel fan rotates within its casing and sucks air from the air space 18, whereby said air is drawn downwardly within the jacket 11 and the casing 17 and discharged through the opening 63 into the fly-wheel casing. In this manner the cylinders are properly cooled.

It is to be understood that the form of my invention herewith shown and described is to be taken as a preferred example of the same and that certain changes in the shape, size, and arrangements of parts may be resorted to without departing from the spirit of the invention or the scope of the subjoined claims.

Having thus described my invention, I claim:—

1. In an engine of the character described, an explosion cylinder, a pumping cylinder connected therewith, a piston operating within the explosion cylinder, a pumping piston connected with the first named piston and operating within the pumping cylinder, a crank shaft, a pitman connected with the crank shaft and the first named piston, a conduit for supplying gas into the pumping cylinder upon the down stroke of the pumping piston and receiving the compressed gas from the pumping cylinder upon the up stroke of the pumping piston, a second conduit for supplying the compressed gas to the explosion cylinder, means for controlling the communication between the first and second named conduits, and a separate pressure relief valve disposed between the first and second named conduits.

2. In an engine of the character described, an explosion cylinder provided with inlet and exhaust ports, a pumping cylinder connected therewith, a working piston operating within the explosion cylinder, a pumping piston connected with the working piston and operating within the pumping cylinder, a crank shaft, a pitman connecting the crank shaft with the working piston, an inlet conduit having communication with the inlet ports of the explosion cylinder, a supply conduit having communication with the pumping cylinder, a gas supply device, a rotatable tubular valve provided with an exterior recess adapted to establish commu-

nication between the gas supply device and the supply conduit and having an opening formed through its wall which leads into the interior of the same to allow of the passage 5 of the compressed gas into said tubular valve when the valve is in one position and the discharge of such compressed gas into the inlet conduit when said valve is moved to another position, means operated by the 10 crank shaft to rotate said valve and means

whereby the charge is automatically returned from the inlet conduit to the supply device when the pressure within the inlet conduit exceeds a predetermined degree.

In testimony whereof I affix my signature 15 in presence of two witnesses.

CHARLES M. LEECH.
